UNITED STATES PATENT OFFICE.

FREDERICK KLEIN, OF COLLEGE POINT, NEW YORK.

SIGNAL APPARATUS.

Application filed September 5, 1924, Serial No. 736,004.

My present invention is shown embodied in a vacuum fuel feed system and in that relation effects a signal to show that the fuel reservoir is empty or that there is an 5 obstruction in the line leading therefrom to the vacuum tank.

Among the objects of the invention are to provide an indicator of the above type which shall be of simple durable and inexpensive construction easily applied and reliable in operation to effect a warning signal when there is still a sufficient residue of fuel to carry the vehicle a reasonable distance.

The invention is not limited in its application to the specific relation mentioned, but in its broader aspects is useful in fluid feed systems whether operated by pressure or by vacuum intermittently or continuously and regardless what the liquid controlled.

A preferred embodiment of the invention includes a closed tank or receptacle disposed in the fuel line between the fuel reservoir and the vacuum tank. Preferably the vacuum chamber of the vacuum tank connects directly with a dip pipe, entering the closed receptacle or chamber of the indicator and low pressure in the dip pipe serves to draw the fuel from the reservoir into the indicator chamber. Whenever the supply fails and the level in the indicator chamber falls below a predetermined point the low pressure in the dip pipe will pneumatically operate an alarm device which may be a visible indicator if desired, but is preferably an audible alarm signal in the nature of a whistle. Features of importance which are preferably incorporated in my device are means for reserving a certain quantity 30 of liquid in the dip pipe in order to compensate for the lag in flow at the beginning of suction in the vacuum tank and means for preventing any siphonic action from the dip pipe into the vacuum tank which would tend to flood the vacuum tank and interfere with proper operation of the system.

Apparatus embodying the invention may be manufactured at comparatively small expense and may be readily attached in the fuel line without any need for employing skilled mechanics. For convenience of attachment I may form the inlet and outlet

ducts to the indicator chamber as short threaded nipples which may be respectively connected to the two threaded members of 55 the usual coupling between the supply line and the intake nipple of the vacuum tank, thus eliminating the necessity for cutting or threading sections of the gasoline supply line. The indicating device may be and 60 preferably is supported directly on the vacuum tank.

Another feature of the invention is the use of a signal controlling valve which is entrained to seating position for shutting 65 off the air duct by the surface friction in the flow of the liquid therethrough. This valve is of wider application in other relations where the flow of liquid is intended to effect some sort of control, for instance, 70 to control the flow of other fluid regardless whether for operating a signal or for some other purposes.

With the above noted and other objects in view, the invention consists in certain novel 75 features of construction and combinations and arrangements of parts as will be more fully hereinafter described and pointed out in the claims.

In the accompanying drawings, 80 Figure 1 is a somewhat diagrammatic view of the vacuum feed system of an automatic vehicle showing the position occupied by my improved alarm device.

Figure 2 is an enlarged vertical, sectional 85 view through the alarm device.

The conventional vacuum feed system of an automotive vehicle includes a gasoline storage tank 10 connected by a pipe line 11 to a vacuum tank 12. A pipe 14 connects 90 the upper end of the vacuum tank with the intake manifold 13 of the engine. Suction is intermittently applied through pipe 14 to the float controlled suction filling chamber 12^a of the vacuum tank, and the suction chamber of the tank intermittently empties 95 into a chamber or emptying tank 12^b which draws to the carburetor 17 through a pipe line 18. The specific construction and operation of the vacuum system need not be set forth in detail, as it is well understood, and taken by itself, is not my invention.

My invention from one important aspect is concerned with the construction and ar-

arrangement of an indicator to give notice that the supply of fuel in the main storage tank is exhausted or that an obstruction exists in the line preventing its flow when suction is applied. The indicator comprises a container shown in its entirety at 20 in Figure 1 and shown in detail in Figure 2. The unit may be provided with legs *a* secured to bracket *b* on the vacuum tank and pipe 11 from the reservoir may deliver to the unit through elbow fitting 33 threaded in the cover 22 which is secured upon the container while a pipe 25' connected to elbow outlet fitting 25 in the cover 22 delivers to the vacuum tank. The cover plate 22 preferably includes a dip pipe 23 which extends preferably nearly to the bottom of the container 1 and is formed with an enlarged threaded upper end 24 into which the outlet nipple 25 may be screwed. A cup-like depression or hemi-spherical cavity 26 in the center of the cover is integrally connected by an air pipe 27 with a tapered valve seat 28 formed in the dip pipe near the lower end thereof. Preferably the cover is cast in one integral piece with the dip pipe, the cavity, the air pipe and the valve seat. An audible signal, such for instance as conventional double convex whistle 29 may be mounted in an annular groove 30 at the upper end of the hemi-spherical cavity. Suction through the nipple 25 will draw air through the duct 27^a in the air pipe and through the whistle to sound the latter unless the duct is cut off as by the bevelled face of a sliding valve 31, which may cooperate with the valve seat in the dip pipe. This valve is preferably of general cylindrical shape and of material which will not float in gasoline or in the particular liquid passing through the system. It normally rests upon the bottom of the container and is formed at its lower end with an approximately semi-circular cut away portion 32 to permit flow of liquid thereunder, through the base 31 in the valve and up the dip pipe. A vent hole 34 is arranged in the dip pipe, preferably below the cover, for purposes appearing hereinafter.

50 The manner of operation is substantially as follows:

Assume the vacuum tank 12 to be empty and the storage tank 10 to be charged and assume also that there is no liquid in the 55 container of the indicator 20. Since the valve 31 is at this time resting on the bottom of container 20, suction applied to the dip pipe from the engine manifold will tend to create a down draft through the duct 27^a thereby sounding the whistle 29. Since, 60 however, the cross sectional area of the dip pipe is considerably greater than the cross sectional area of the air duct and in view of the fact that the dip pipe is open to the 65 interior of the container both through the

valve 31 and the vent hole 34, air will be withdrawn from this chamber and flow of gasoline from the storage tank is initiated by suction. The alarm will continue to sound until the liquid reaches the lower end of the dip pipe, at the level *a*—*a*. Suction continuing, the liquid will then start, to be drawn upward in the dip pipe past gate 32 and upward through the bore 31' of the valve. The flow of liquid through this restricted passage and up through the dip pipe will serve to lift the valve, not by flotation however, but rather by the mechanical action or surface friction of the upwardly flowing liquid. The valve, upon being moved upward against its seat 28 will cut off the air duct to the whistle and consequently stop the signal from sounding. Inasmuch as the passage through the control valve is smaller than the cross sectional area of the dip pipe continuing suction in the dip pipe will not only pull gasoline into the vacuum tank but will continue to suck air from the interior of the container through the vent hole 34 until the vent hole is sealed by the liquid level rising to the line *b*—*b*, at which point balance or equilibrium is established.

In the ordinary operation of the vacuum tank, the suction is intermittently applied, the suction chamber 12^a of the vacuum tank being intermittently filled and emptied. After the suction chamber of the tank has been filled therefor, suction in the dip pipe 23 will cease. Any substantial siphonic action which might tend to drain the higher signalling container 20 even when no suction is applied to the lower vacuum tank is prevented by the uncovering of the vent hole 34. When the application of suction from the vacuum tank ceases, the valve 31 drops to the bottom, but the duct 27^a will be liquid sealed by the gasoline standing in the dip pipe. Before this duct can again be exposed, and in fact shortly after suction is again applied, the valve 31 will again rise by the surface friction of the flowing liquid and will positively cut off the air passage. Thus, whenever in the operation of the vacuum tank, suction is applied through nipple 25, fuel is thereby withdrawn from container 20 and admitted to the vacuum tank, while the level in container 20 is maintained substantially constant at line *b*—*b* by entry of fuel drawn from the reservoir.

Whenever the flow of liquid through inlet 33 is interrupted either by an obstruction in the gasoline supply line or because the reservoir is empty, the contents of the container 20 will be withdrawn until the liquid level falls to *a*, *a* or just below the lower end of the dip pipe, whereupon the flow of air alone, being insufficient to maintain the control valve raised, the latter drops and the whistle will be sounded by the air now sucked there-

through. The whistle is sounded therefor when there is still a residual supply of gasoline in the vacuum tank which would ordinarily be sufficient to carry the vehicle to the 5 nearest filling or service station.

It will be understood that while I have shown an ordinary bi-convex whistle signal and while this type is preferred other indicating devices may be used to advantage.

10 The field of usefulness of my apparatus is not limited to fuel supply systems but may be used as a flow indicator in various systems whether operated by vacuum or pressure. In the claims I use the terms pressure 15 differential as generic to pressure or vacuum operation. Where the liquid is conveyed by a force-feed operation, the pneumatic signal would of course, be sounded by blowing out rather than sucking in, the valve construction 20 remaining the same as heretofore described.

My attachment may be easily applied in the relation shown without the services of an expert mechanic, may be readily assembled and disassembled for purposes of cleaning and repair. Obviously the container 25 may be mounted in relations other than that specifically shown.

Where a float valve is used, strength and 30 durability is ordinarily sacrificed for lightness and said float is subject to disorder and to jamming where on the other hand, my solid unitary liquid-entrained valve is thoroughly reliable.

35 The valve arrangement shown while preferred in the specific relation described, is more generic application in numerous other relations whether for signalling or for other purposes. It will be seen that this valve may 40 serve, for instance, to control a port for liquid or gas flow responsive to the flow of another liquid.

It will thus be seen that there is herein 45 described apparatus in which the several features of this invention are embodied, and which apparatus in its action attains the various objects of the invention and is well suited to meet the requirements of practical use.

50 As many changes could be made in the above construction and many apparently widely different embodiments of this invention could be made without departing from the scope thereof, it is intended that all matter 55 contained in the above description or shown in the accompanying drawings shall be interpreted as illustrative and not in a limiting sense.

Having thus described my invention what 60 I claim as new and what I desire to secure by Letters Patent is:

1. A fluid controlled system including a source of liquid, a pipe, means applying a pressure differential to cause flow of liquid 65 from said source through said pipe, a duct

communicating with said pipe and a valve in the path of liquid flow and movable to close the duct under a predetermined condition of liquid flow.

2. A liquid supply system including a 70 pipe, through which liquid will flow by pressure differential, an air duct communicating with the pipe, a signal associated with said duct and responsive to the flow of air through said duct and a valve in the path 75 of liquid flow movable to air duct closing position under a predetermined condition of liquid flow.

3. A liquid supply system including a 80 pipe, through which liquid will flow by pressure differential, and air duct communicating with the pipe, a signal associated with said duct and responsive to the flow of air through said duct, and a valve in the path 85 of liquid flow and movable to air duct closing position by the surface friction of the flowing liquid.

4. A liquid supply system including a 90 pipe, through which liquid will flow by pressure differential, an air duct communicating with the pipe, a signal controlled by the air duct, a valve in the pipe for cutting off the air duct and movable to air duct closing position by the surface friction of the liquid flowing through the pipe, said 95 valve being constructed and arranged to be maintained out of air duct closing position when the surface friction caused by liquid flow is below a predetermined minimum.

5. A device of the class described in claim 100 4 wherein the flow pipe is vertically disposed and the flow of liquid is upward therethrough so that in the absence of the liquid flow the valve is held out of air duct closing position by gravity.

6. A liquid flow indicator of the type including a pipe through which liquid, the flow of which is to be indicated is propelled under differential pressure, said indicator having an air duct communicating therewith, a signal associated with said duct, and responsive to air flow therethrough and a sliding valve movable into and held in air duct closing position by the action of the liquid flowing through the pipe.

7. In a vacuum feed system, a vacuum 110 tank including a vacuum filling chamber and an emptying chamber, an indicator chamber in the feed fuel lines in series with the first mentioned chambers and having sounding means adapted to be pneumatically operated by suction of the feed system upon failure of liquid supply and a control member entrained by fuel flow to interrupt suction communication with the sounding means.

8. In combination a tank, a container, a line through which liquid is removed from the container, said line extending into the container, an air line communicating with said first line, a valve controlled by liquid 120 125

withdrawn through said first line and adapted to cut off the air line and a signal responsive to the flow of air through the air line and operable when the rate of withdrawal of the liquid from the container is less than a predetermined minimum and a source of differential pressure for propelling the liquid and operating the signal.

9. In combination, a container, a vacuum line through which liquid is drawn from the container, said vacuum line terminating in a suction pipe which extends into the container, an air line communicating with the suction pipe, a valve controlled by liquid drawn through the suction pipe and adapted to cut off the air line and a signal pneumatically controlled by the air line and operable when the liquid level in the container falls below a predetermined level.

10. In combination, a container, a vacuum line through which liquid is drawn from the container, said vacuum line terminating in a suction pipe, which dips into the container, an air line communicating with the dip pipe, a valve controlled by liquid drawn through the dip pipe and adapted to cut off the air line, and a signal pneumatically controlled by the air line and operable when the liquid level in the container falls below the lower end of the dip pipe.

11. A container, means for delivering liquid thereto, a vacuum line terminating in a dip pipe disposed within the container, for withdrawing liquid from the container, an air duct communicating with the dip pipe, a slide valve correlated with the dip pipe controlled by the surface friction of liquid sucked therethrough and adapted to cut off the air duct and a signal actuated by flow of air through the duct and operable when the liquid in the container falls below a predetermined level.

12. The combination set forth in claim 10 in which a vent is provided at the upper end 45 of the dip pipe for preventing the contents of the pipe and container from being siphoned out in the absence of suction.

13. An alarm device of the class described including a liquid receptacle, a pipe dipping 50 into the receptacle and through which liquid is adapted to be withdrawn, a signal controlling air duct opening into the dip pipe, a slide valve in the dip pipe operable by liquid flow to cut off the air duct, said air duct 55 being normally sealed by the liquid in the container upon cessation of suction in said pipe.

14. In a device of the class described, a container, a suction dip pipe extending into 60 the container, an inlet through which liquid is adapted to be drawn into the container by suction through said dip pipe, a signal, an air duct controlling the same and communicating with the dip pipe, a cylindrical slide 65 valve in the dip pipe operable under the in-

fluence of liquid flow therethrough to cut off the air port and adapted to gravitationally descend from air port closing position upon cessation of such flow.

15. In a device of the class described a container, a suction dip pipe extending thereto, an inlet through which liquid is adapted to be sucked into the container, a signal, an air duct controlling the same and communicating with the dip pipe, a slide valve 70 in the dip pipe, operable under the influence of liquid flow therethrough to cut off the air port and adapted to gravitationally descend from air port closing position upon 75 cessation of such flow and a vent in the dip pipe for preventing liquid from being siphoned from the reservoir when no suction is applied.

16. In a device of the class described, a container, a suction dip pipe extending thereto, an inlet through which liquid is adapted to be sucked into the container, a signal, an air duct controlling the same and communicating with the dip pipe, a cylindrical slide valve in the dip pipe operable under 80 the influence of liquid flow therethrough to cut off the air port and adapted to gravitationally descend from air port closing position upon 85 cessation of said flow and a vent near the upper end of the dip pipe and within the container determining the normal liquid level and preventing siphonic action from the dip pipe when no suction is applied.

17. In a device of the class described a container, a suction dip pipe extending thereto, an inlet through which liquid is adapted to be sucked into the container, a signal, a slide valve in the dip pipe controlling the operation of the signal and operable under 90 the influence of liquid flow therethrough to cut off the air port and adapted to gravitationally descend from air port closing position upon 95 cessation of such flow, said slide valve having a cut away portion near its lower end offering a passage way for the 100 flow of liquid therethrough to initiate upward movement thereof.

18. In a vacuum feed system, the combination with an engine intake manifold of a vacuum tank operated therefrom, a storage 115 tank and a pipe line connecting them, an alarm unit adjacent the vacuum tank operated pneumatically from the intake manifold, and in the path of liquid flow from the storage to the vacuum tank and a control 120 member normally in position to permit pneumatic operation of the alarm unit and entrained by the flow of liquid through the alarm unit to interrupt the application of suction for alarm operation.

19. In a vacuum feed system, the combination with an engine intake manifold of a vacuum tank operated therefrom, a storage tank and a pipe line connecting them, of a liquid receptacle in the pipe line and sup- 125 130

ported from the vacuum tank, an alarm device associated with the receptacle for pneumatic operation from said manifold in order to indicate failure of liquid flow from the 5 storage tank and a control member normally in position to permit pneumatic operation of the alarm unit and entrained by

the flow of liquid through the alarm unit to interrupt the application of suction for alarm operation.

Signed at New York in the county of New York and State of New York this 3rd day of September, A. D. 1924.

FREDERICK KLEIN.
